DES. 1948

George K. Jackson, of New York, N.Y.

Assigns to

Himself & Burnet & Co. of the same place.

Letters Patent No. 1948-Dated May 24th 1864.

Design for a Stall Guard.

The schedule referred to in these Letters Patent and making part of the same.

Stall whom it may concern:

Be it known that I, George K. Jackson, of the City, County and State of New York, have invented or produced a new and original design for a Guard for Horse Stalls; and I do hereby declare that the following is a full, clear and exact description thereof, which will enable others skilled in the art to make and use the same, reference being had to the accompanying drawing making a part of this specification, said drawing being a side view of my stall guard constructed according to my design.

This design relates to, or is intended for, a cast-iron guard which is placed on the top of partitions or sides of horse stalls.

The back end, a, of the guard is vertical and its lower edge b, at right angles with the back end a, the top c, being curved in serpentine form so that the front end of c, will meet or connect with the front part of the lower edge b, as shown in the drawing.

The guard is provided all around with what may be termed a border composed of bars or strips d, d, be-

DES. 1948

tween which there are rings e, at equal distances apart connected by bars or links f.

The space within this border is filled with bars g, in reticulated form and at each corner at the back end of this space there is a scroll h. The front end of the guard also terminating in a scroll h.

Having thus described my invention, what I claim as new and desire to secure by Letters Patent, is -

The design for a Guard for Horse Stalls composed of a border formed of strips d, with rings e, connected by bars or links f, between them and the space within the border filled with bars g, placed in reticulated form and the scrolls h, h, h, substantially as described.
